(57) **CLAIM**

The ornamental design for an end piece for ink cartridge for ink jet printer, as shown and described.

DESCRIPTION

FIG. 1 is a front view of an end piece for ink cartridge for ink jet printer showing our new design;

FIG. 2 is a top plan view thereof;

FIG. 3 is a bottom plan view thereof;

FIG. 4 is a left side view thereof;

FIG. 5 is a right side view thereof;

FIG. 6 is a perspective view as viewed from front and bottom direction thereof; and,

FIG. 7 is a perspective view as viewed from rear and top direction thereof.

The broken lines are for purposes of illustration only and form no part of the claimed design.
